DESIGN FOR A STATUETTE

Daniel J. Conley, Seattle, Wash.

Refiled for abandoned application Serial No. 74,694, January 29, 1938. This application March 28, 1939, Serial No. 83,886. Term of patent 14 years

To all whom it may concern:

Be it known that I, Daniel J. Conley, a citizen of the United States, residing at Seattle, in the county of King and State of Washington, have invented a new, original, and ornamental Design for a Statuette, substantially as shown, of which the following is a specification, reference being had to the accompanying drawing, forming part thereof.

This is a refiled application for my abandoned application filed January 29, 1938, Serial Number D-74,694.

I claim:

The ornamental design for a statuette, as shown.

DANIEL J. CONLEY.
